CUSHIONED KEY FOR WRITING MACHINES

Filed, July 17, 1933

Lewis A. Amis

INVENTOR

BY *Lewis A. Amis*
ATTORNEY

- said top and a coiled spring reposing in said cup to exert a continuous force against the underside of said top.
2. As a new article of manufacture, a type-
5 writer key including a resilient top and a base comprising an annular ring and having an annular, inwardly extending rib spaced from its bottom, said base being arranged to receive the lower portion of said resilient top, a flanged cup
10 member retained by said annular rib for locking the lower portion of said resilient top within said ring, and a coiled spring reposing within said cup for supporting said resilient top. 80
3. As a new article of manufacture, a type-
15 writer key including a resilient top and a base comprising an annular ring, an inwardly and downwardly extending flange integral with the upper portion of said annular ring and arranged to be received within an annular groove in said 85
- 20 cup for supporting said resilient top. 90
